C. A. SOANS.
DRYING FRAME.
APPLICATION FILED NOV. 28, 1916.

1,237,967.

Patented Aug. 21, 1917.

Cyril A. Soans

UNITED STATES PATENT OFFICE.

CYRIL A. SOANS, OF CHICAGO, ILLINOIS.

DRYING-FRAME.

1,237,967.

Specification of Letters Patent. Patented Aug. 21, 1917.

Application filed November 28, 1916. Serial No. 133,964.

To all whom it may concern:

Be it known that I, CYRIL A. SOANS, a citizen of the United States, residing at Chicago, in the county of Cook and State of Illinois, have invented new and useful Improvements in Drying-Frames, of which the following is a specification.

My invention relates to improvements in drying frames and refers particularly to a drying frame which may be used in conjunction with the ordinary radiator usually installed in dwelling houses or apartments.

The principal objects of the invention are to provide a drying frame which may be applied to an ordinary steam or hot water radiator; to provide a drying frame which is capable of being applied to radiators of varying lengths or of different cross sections; to provide a drying frame which is capable of being supported rigidly and securely on an ordinary radiator of the class described without the aid of extraneous support or fastening devices; to provide a drying frame of the class described which may be removed from or applied to a radiator without the necessity of making mechanical adjustments; to provide a drying frame of the class described which may be collapsed or folded flat for shipping or storage purposes; to provide a frame of the class described in which substantially the entire heat emanating from the radiator is employed in the drying of the clothes hung upon the frame; to provide a drying frame of the class described which shall have a large clothes capacity, while at the same time being comparatively inconspicuous and compact, and which does not obstruct valuable room space; to provide a drying frame of the class described which may be made of inexpensive material and which shall be simple in design and substantial in construction, and, in general to provide an improved drying frame of the character referred to.

In the drawings which accompany this application, Figure 1 is an elevation of the frame applied to a radiator. Fig. 2 is a front elevation of the frame and radiator shown in Fig. 1, and Fig. 3 is a section taken on the side 3—3 of Fig. 1.

Referring to the drawings, 10 represents a multi-coil cast iron radiator of the type usually installed in houses or apartments,

and which may be heated by either steam or hot water. As shown, the radiator stands on the floor 11, adjacent to the side wall 12. The main elements of the frame comprise a frame proper consisting of a pair of opposed side bars 13 and 14, between which side bars extend a series of rods 15 upon which the clothes are hung or draped. The frame proper is pivotally supported on a horizontal axis at the upper ends of a pair of uprights 16 and 17, and the frame proper may be adjusted at any angle by means of the wing nuts 18 and 19 on the pivot bolts 20 and 21 which extend through the side bars and the uprights.

The lower ends of the uprights 16 and 17 are extended downwardly at the front of the radiator and their lower ends are connected by means of a wooden bar or strip 22 which prevents the lower end of the supporting structure from swinging toward the wall. The weight of the device is borne principally by the top strip 23 nailed to the front strip 24, the latter being also nailed to the rear faces of the uprights 16. It will be observed that the strip 23 rests upon the top of the ornamental curved portion 25 of the radiator coils 26, and the front strip 23 engages the fronts of said curved portions 25, thereby preventing bodily movement of the structure toward the wall.

The tops of the uprights 16 and 17 carrying the frame proper are prevented from swinging outwardly into the room by means of a hook member which engages the rear faces of the rear ornamental curved portion 26 of the coils of the radiator, said parts 26 thus constituting abutments which prevent said outward swinging movement of the frame. The hook member which engages the parts 26 comprises a rear bar or strip 27 nailed to a top-strip 28, the said top strip 28 being also nailed to a pair of cross members 29 and 30 extending across the top of the radiator and adjustably connected to the uprights 16 and 17 by bolts 31 and 32. The bolts 31 and 32 are equipped with wing nuts 33 and 34 so as to enable the cross bars 29 and 30 to be placed in different angular positions with reference to the uprights 16 and 17. It is manifest that after the wing nuts 33 and 34 having been screwed up tight with the parts in the position shown in Fig. 1, the supporting structure is rigidly

and securely mounted upon the radiator without any tendency to swing or tip over either to or from the wall 12.

To accommodate the device to radiators 5 having different sizes of coils, I prefer to make the cross bars 29 and 30 adjustable in length so as to cause the top of the radiator to fit rather closely between the front strip 24 and rear strip 27. This adjustability of 10 the bars 29 and 30 is provided by making each bar in two pieces which telescope or slide with reference to each other.

For instance, as best shown in Figs. 1 15 and 3 the part 29' constitutes the front end of the two piece bar 29, the alinement of the two parts of the bar being preserved by the tongue and groove joint 35. When the bars 29 and 30 have been adjusted to the proper 20 length by sliding the parts 29 and 29' relative to each other they are locked in position by means of a clamping bolt 36 and wing nut 37, the bolt extending through a hole in the part 29' and through a long slot 38 in the outer piece of the cross bar 29. Spreading 25 of the open forked ends 39 and 40 when the cross bar is fully extended is prevented by a small clip 40' apertured to receive the bolt 36 and having its ends bent over the outside edges of the slotted parts of the 30 cross bar, as shown at 41 and 42. In order to increase the capacity of the drying frame for small articles which may be conveniently hung from a single point of support, I prefer to furnish the upper ends of the side 35 bars 13 and 14 with a plurality of outstanding pegs 43.

The device may be folded or collapsed 40 into very small compass by releasing the thumb nuts 20 and 21 and swinging the lower end of the frame proper down between the uprights 16 and 17, while at the same time the thumb nuts 33 and 34 are released and the cross bars 29 and 30 are swung up into such position that the side bars lie along 45 the outside of the upper parts of the uprights 16 and 17. The device may be thus folded into a flat package which occupies an extremely narrow space, enabling it to be shipped readily or stored conveniently when 50 not in use. For instance, when so folded, the device may be slipped down into the space between the wall 12 and the coils of the radiator.

As a drying frame, the frame is extremely 55 efficient for the reason that the heated air currents produced by the radiator are almost entirely intercepted by the clothes suspended from the bars 15, the wall 12 constituting a baffle which throws the rising currents of air outwardly into the room to some extent, so that the clothes hung on the front of the device are efficiently dried as well as the clothes hung directly over the radiator.

60 55 The device being wholly supported by the

radiator does not obstruct valuable floor space and, although the lower end of the inclined frame proper, when the device is in use, projects slightly out into the room, the space occupied is negligible and if such space is temporarily needed for the swinging of a door, or required for any other purpose, it is a simple matter to swing the frame into vertical position temporarily, even though the frame is at the time draped 75 with clothing.

I have described in this specification only a single application of my invention which may be embodied in other forms without sacrifice of efficiency. The scope of the 80 invention must, therefore, be determined by referring to the appended claims.

I claim:

1. Means for detachably mounting a drying rack upon a suitable support comprising 85 a member extending upwardly and downwardly from the top of the support, to the upper extension of which the rack is secured, the lower extension being arranged to engage a front facing portion of the support 90 and a part secured to said member and engaging a rearwardly facing portion of the support for preventing swinging movement of said member, the arrangement including a downwardly facing part secured to said 95 member and engaging an upwardly facing portion of the support for supporting the weight of the structure.

2. Means for detachably mounting a drying rack upon a suitable support comprising 100 a pair of spaced apart members extending upwardly and downwardly from the top of the support to the upper extensions of which the rack is pivotally secured, the lower extensions being arranged to engage 105 a front facing portion of the support and a part secured to said members and engaging a rearwardly facing portion of the support for preventing swinging movements of said members, the arrangement including a 110 downwardly facing part secured to said members and engaging the top of the support for supporting the weight of the structure.

3. Means for detachably mounting a drying rack composed of a connected series of horizontal clothes rods upon a suitable support comprising a pair of spaced apart 115 members extending upwardly and downwardly from the top of the support to the upper extensions of which the rack is pivotally secured, a member connecting the lower ends of said members and engaging a front facing portion of the support and a hook member secured to intermediate portions of said members and engaging a rearwardly facing portion of the support for preventing swinging movements of said members away from the support and a downwardly facing part secured to intermediate 120 125 130

portions of said members and resting upon an upwardly facing portion of the support for bearing the weight of the structure.

4. Means for detachably mounting a drying rack upon a suitable support comprising a pair of spaced apart members extending upwardly and downwardly from the top of the support, the drying rack being secured to upper portions of said members, a pair of 10 adjustably spaced opposed parts connected to intermediate points of said members and engaging opposite sides of said support for positioning the intermediate portions of said members, means on the lower ends of 15 said members and engaging one of the said sides of said support for preventing movement of the lower ends of said members and a downwardly facing part secured to intermediate portions of said members and engaging an upwardly facing portion of the support for bearing the weight of the structure.

5. A drying frame adapted to be mounted upon a support comprising a series of horizontal spaced apart clothes rods, a pair of opposed side bars carrying said rods; a pair of spaced apart uprights upon which said side bars are pivoted on a horizontal axis, said uprights having their lower ends extended below the top of the support and outside of the support, means connected to the lower ends of said uprights for preventing movement of the latter inwardly of the support; means secured to intermediate 30 portions of said uprights for preventing said intermediate portions from moving inwardly of the support and for supporting the weight of the structure on top of the support and a hook member connected to 35 said uprights and engaging a rearwardly facing portion of said support for preventing outward movement of the tops of the uprights, said hook member being adjustable in length and pivotally connected to 40 said uprights.

6. A drying frame adapted to be mounted

upon a support comprising a series of horizontal spaced apart clothes rods, a pair of opposed side bars carrying said rods; a pair of spaced apart uprights upon which said side bars are pivoted on a horizontal axis, said uprights having their lower ends extended below the top of the support and outside of the support, means connected to the lower ends of said uprights for preventing the movement of the latter inwardly of the support; means secured to intermediate portions of said uprights for preventing said intermediate portions from moving inwardly of the support and for supporting the weight of the structure on the top of the support and a hook member connected to 55 said uprights and engaging a rearwardly facing portion of said support for preventing outward movement of the tops of the uprights, said hook member being adjustable in length and pivotally connected to 60 said uprights.

7. A drying frame for mounting on the top of a support comprising a pair of side bars, horizontal clothes rods extending between said side bars, a pair of spaced apart uprights 70 to which intermediate portions of said side bars are pivotally connected, said uprights having their lower ends extended down below the top of the support, but outside of the side plane of the latter, a strip connecting the lower end of said uprights and engaging a side of the support, a strip connecting said uprights adjacent to the top of the support and also engaging the upper portion of the support, extensible members 75 extending across the top of the support and connected to said uprights, a strip secured on the ends of said extensible members and engaging the support on the side remote from the uprights, and means for 80 locking said extensible members in adjusted position.

CYRIL A. SOANS.
